Primary Examiner — Bridget L Eland(74) *Attorney, Agent, or Firm* — Arch & Lake LLP(57) **CLAIM**

The ornamental design for a mobile phone, as shown and described.

DESCRIPTION

FIG. 1 is a front view of a mobile phone showing my new design.

FIG. 2 a back view thereof.

FIG. 3 is a left view thereof.

FIG. 4 is a right view thereof.

FIG. 5 is a top view thereof.

FIG. 6 is a bottom view thereof.

FIG. 7 is a front and right side perspective view thereof; and, FIG. 8 is a back and left side perspective view thereof.

The broken lines in the drawings are for the purpose of illustrating portions of the mobile phone that form no part of the claimed design.

1 Claim, 7 Drawing Sheets(56)
